(57) CLAIM

The ornamental design for a shoe, as shown and described.

DESCRIPTION

Fig. 1.1 is a perspective view showing my new design;

Fig. 1.2 is a right view thereof;

Fig. 1.3 is a left view thereof;

Fig. 1.4 is a front view thereof;

Fig. 1.5 is a rear view thereof; and

Fig. 1.6 is a top view thereof.

The broken lines on the shoe represent stitching and form no part of the claimed design.
